(57) **CLAIM**

The ornamental design for a template guide for use with a woodworking tool as shown and described.

DESCRIPTION

FIG. 1 is a top, front, right side isometric perspective view of a template guide for use with a woodworking tool in accordance with my design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a sectional taken in the direction of 8-8 of FIG. 6. The broken lines illustrate portions of the template guide for use with a woodworking tool which form no part of the claimed design.
